MAGNETO.

APPLICATION FILED JUNE 23, 1919.

Patented Nov. 14, 1922.

2 SHEETS—SHEET 2.

Inventor:
Henry G. Cox,
By Chas. E. Lord,
Atty.

UNITED STATES PATENT OFFICE.

HENRY G. COX, OF CHICAGO, ILLINOIS, ASSIGNOR TO INTERNATIONAL HARVESTER COMPANY, A CORPORATION OF NEW JERSEY.

MAGNETO.

Application filed June 23, 1919. Serial No. 306,034.

To all whom it may concern:

Be it known that I, HENRY G. Cox, a citizen of the United States, residing at Chicago, in the county of Cook and State of Illinois, have invented certain new and useful Improvements in Magnetos, of which the following is a full, clear, and exact specification.

This invention relates to magnetos, and 10 more particularly to the construction of armatures for magnetos.

As is well-known, the armature is the most expensive part of a magneto to manufacture, this being due to the fact that ordinarily the armature coil must be wound manually on the armature frame. This manual operation is necessarily time consuming and therefore the armature is an expensive part to make compared to the other 20 parts of the magneto. The ordinary type of magneto armature is, moreover, more or less unsatisfactory, since the various parts of the armature are fitted together in such a way that if the necessity arises for their 25 being taken apart, they cannot readily be assembled in such a manner that the alignment of the parts is satisfactory, and for this reason a repaired armature is often defective.

30 The present invention, therefore, has for its object to provide an armature for magnetos and machines of like character that will be light in construction, but will also be rigid and stiff and able to withstand the 35 stresses to which devices of this character are put.

A further object is to provide an armature that can be easily and quickly taken apart and can be accurately assembled without 40 throwing the parts out of true alignment, thereby furnishing a construction that may be easily and effectively repaired.

Another object of the invention is to provide an improved construction of armature 45 core by employing material of great magnetic conductivity, whereby the efficiency of the armature in operation is increased.

A still further object is to provide a construction of armature in which a formed 50 winding may be utilized for the armature coil, this form of construction materially reducing the cost of the armature since the coil can be wound on an automatic machine instead of manually.

55 With these and other objects in view,

which will appear as the description proceeds, my invention consists briefly of an armature construction in which an armature frame is used, this frame preferably being cast and having open sides. A formed 60 winding or a wound armature coil is placed within this armature frame and is retained therein by means of the armature core.

In order to make a complete disclosure of the invention, the improved construction has 65 been illustrated in the accompanying drawings, and in these drawings—

Fig. 1 is a transverse sectional view through the magneto illustrating the improved construction of armature; 70

Fig. 2 is a sectional view taken at right angles to Fig. 1;

Fig. 3 is an end elevation of the magneto;

Fig. 4 is a perspective view showing the construction of armature frame; 75

Fig. 5 is a perspective view illustrating one embodiment of the armature pole shoe and core, this form of construction being shown in section in Fig. 1;

Fig. 6 is a perspective view showing a 80 modified construction of pole shoe;

Fig. 7 is a perspective view showing one construction of an armature core;

Fig. 8 is a transverse sectional view through the armature core and pole shoes 85 illustrating one mounting of the core shown in Fig. 7;

Fig. 9 is a transverse sectional view similar to Fig. 8, but showing another mounting of the core and pole shoes; and 90

Fig. 10 is a sectional elevation of the construction shown in Figs. 8 and 9.

In Figs. 1 and 2 I have illustrated a construction of magneto comprising a frame having a base 20, and a box-like frame structure 21 preferably formed integral with the base, the frame 21 and base 20 being formed of non-magnetic material, such, for instance, as zinc alloy. Permanent magnets 22 are secured in any suitable manner to the base 100 20 and frame 21, and pole pieces 23 are carried by the frame 21 in a manner to retain them in contact with the poles of the permanent magnets 22. Suitable end plates 105 24 and 25 are secured to the ends of the frame 21 and are formed with bearings 26 in which the armature is rotatably mounted. No invention per se is claimed for the construction just described and any other suitable form of magneto frame may be employed. 110

The armature comprises an armature frame 27 formed of non-magnetic material, such as aluminum, this frame being preferably die-cast and having cast therewith outwardly projecting stub shafts 28 and 29. The frame 27 has formed at its ends annular lips 30 which act in a well-known manner to fling the oil which is used in lubricating the parts outwardly, thereby preventing any of the oil from coming in contact with the insulated winding of the armature. An oil exit opening 31 is formed in each of the end plates to permit the discharge of the oil. As stated above, a formed winding or a wound coil is used in connection with my armature, and this coil is indicated at 32 and may consist of a single winding or of a primary and secondary winding if the armature is to be used for high tension magnetos. In the drawings I have illustrated the construction for a low tension magneto consisting of a single coil. The coil 32 is placed within the open rectangular armature frame 27 and is retained therein in the following manner. Referring to Fig. 1, I have illustrated one construction of retaining means, this construction comprising core pieces 33 formed with inwardly extending portions 34 and pole shoes 35. This core construction may be formed of low carbon steel, or of cast iron and the core pieces secured in place by means of transverse rivets 36 which extend through the core and pole shoes and are headed over in a manner to securely retain the core pieces and the coil 32 in place on the armature frame 27. As illustrated in Fig. 4, I have devised means for properly positioning the pole shoes, this means comprising outwardly extending dowel pins 37 which co-operate with dowel holes 38 formed in the pole shoes.

It has been found that although the form of core construction shown in Fig. 1 and just described gives satisfaction, a construction of armature core in which a softer grade of iron can be used is still more satisfactory, since this grade of iron possesses greater magnetic conductivity, and therefore cores made of this grade of iron will reverse their polarity much more easily. A construction has been worked out, therefore, utilizing this softer grade of iron, such as Norway iron, and this construction is illustrated in Figs. 7, 8, 9 and 10. The construction illustrated also makes use of the fact that a plurality of comparatively small parallel conductors is more satisfactory for conducting magnetism than a single larger conductor, since the small conductors, when held in close contact with each other, have less residual magnetism, are not as subject to local currents and eddy currents, and for these reasons reverse their polarity much more easily. As above stated, the conductors in this instance are formed of a very soft grade of Norway iron, a plurality of these small conductors

39 being bound tightly together by means of a metallic tube 40 which may be formed of steel or of any other suitable metal, if desired. The package of conductors 39 is passed through the opening in the coil 32, and in one embodiment of the invention (see Fig. 8) I have shown pole shoes 41 positioned in contact with the outer ends of the conductors 39, the pole shoes being securely held in contact with the core by means of transverse rivets 42 similar to the rivets 36 shown in Fig. 1.

Another method of securing the core in place is illustrated in Fig. 9 where the pole shoes 43 are shown as recessed, the core being longer than that shown in Fig. 8 and extending into the recesses of the pole pieces. Suitable rivets 44 are used as in the other forms to retain the pole pieces and core on the armature frame 27. The form of construction shown in Fig. 9 has the advantage of using a greater amount of soft iron core, thereby increasing the magnetic conductivity of the armature.

In Fig. 2 I have illustrated one method of conducting the current from the armature coil, a leadwire 45 being secured to the coil and to a spring 46, the spring contacting at its outer end with a brush 47 from which the current is taken by means of any suitable clip or connector 48. In the form of construction illustrated, the brush, spring and leadwire are carried by a hollow plug 49, preferably formed of brass, and mounted in a bushing 50 formed of non-conducting material and carried by the hollow shaft 29. The shaft 29 is provided with an inwardly extending rib 51, and the plug 49 is secured against endwise and rotative movement by means of a nut 52 spaced from the rib 51 by a washer 53 which is formed of insulating material and is disposed on one side of and contacts with one side of the rib 51. Another insulating washer 54 is interposed between the other surface of rib 51 and the plug 49. Any other means for conducting the current from the armature coil may be employed, if desired, the particular form illustrated and described being shown merely for the purpose of disclosing one method for accomplishing this end.

Having described the construction of my improved armature, I will now set forth briefly the method of assembling the armature and of taking the various elements apart, should this be necessary for repair purposes or for other reasons.

First, the prepared coil 32 is placed within the open frame 27. If the construction shown in Fig. 1 is employed, the portions 34 of the core pieces 33 are passed within the opening of the coil from the opposite sides thereof, and the rivets 36 are then passed through the core pieces and are headed over, securely retaining the various parts

together. If the form of core illustrated in Figs. 8 and 9 is utilized, the core package is passed through the opening in the coil, and then the pole shoes are placed in position 5 and the rivets are passed through the shoes and core. If, for any reason, it is desired to take the armature apart, it is merely necessary to file off or otherwise remove the heads of the rivets, whereupon the pole shoes 10 or core pieces may be withdrawn from the coil, permitting the removal of the coil from the armature frame.

The advantages of the improved construction have already been fully set forth in this 15 specification, and a further statement is therefore believed to be unnecessary.

While certain embodiments of the invention have been illustrated in the accompanying drawings, it should be understood that 20 I do not intend to be limited to the particular constructions shown, but that further changes and modifications may be made without departing from the spirit and scope of the invention, as expressed in the following 25 claims.

I claim:

1. In an armature, an integral frame having open sides, a coil disposed within the frame, and means comprising pole pieces 30 for removably securing the coil in the frame and closing the sides thereof.
2. In an armature, an integral frame having open sides, a coil disposed within the frame, a core disposed within the coil and 35 means comprising pole pieces for removably securing the coil in the frame and closing the sides thereof.
3. In an armature, an integral frame having open sides, a coil disposed within said 40 frame and having an opening therethrough, a core disposed in the opening of said coil and comprising a plurality of parallel mag-

netic conductors, and means for retaining said core and said coil within said frame.

4. In an armature, an integral frame 45 formed of non-magnetic material and having open sides, a coil disposed within said frame and having an opening therethrough, a core removably disposed within the opening of said coil, pole shoes contacting with 50 said core, and means for retaining said pole shoes in contact with said core.

5. In an armature, an integral frame of non-magnetic material and having stub shafts integral therewith, a coil disposed 55 within said frame, and means formed of magnetic material for removably securing said coil in said frame.

6. In an armature, a frame, a coil disposed within said frame, a core disposed within 60 said coil, pole shoes having recessed portions receiving said core, and means passing through said pole shoes and said core for retaining said core in said coil and said coil in said frame. 65

7. In an armature, a frame, a coil disposed within said frame, a core disposed within said coil, pole shoes contacting with the ends of said core, and means passing through said pole shoes and said core for retaining said 70 core and said coil in said frame.

8. In an armature, a frame, a coil disposed within said frame, a core disposed within said coil comprising a plurality of tightly bound parallel magnetic conductors, 75 pole shoes having recessed portions receiving said core, and means passing through said pole shoes and said core for retaining said core in said coil and said coil in said frame. 80

In testimony whereof I affix my signature.

HENRY G. COX.
